[57] CLAIM

The ornamental design for a mattress for doll, as shown and described.

DESCRIPTION

FIG. 1 is a perspective view, as viewed from the top, of a mattress for doll, showing my new design;

FIG. 2 is a right side elevational view thereof, the left side elevational view being a mirror image thereof;

FIG. 3 is a front elevational view, the rear elevational view being a mirror image thereof;

FIG. 4 is a top plan view thereof with the article in open condition;

FIG. 5 is a bottom plan view thereof; and,

FIG. 6 is a perspective view thereof similar to FIG. 1, with the article in folded condition.

1 Claim, 3 Drawing Sheets
